US00D847830S

(12) **United States Design Patent** (10) **Patent No.:** **US D847,830 S**
Chapman et al. (45) **Date of Patent:** **** May 7, 2019**

(54) **DISPLAY SCREEN OR PORTION THEREOF
WITH GRAPHICAL USER INTERFACE**

- (71) Applicant: **General Electric Company**, Schenectady, NY (US)
- (72) Inventors: **Philip E. Chapman**, Oregon, WI (US); **Robert Q. Tham**, Middleton, WI (US); **Michael Foulis**, Madison, WI (US); **Wesley Moreau**, Cottage Grove, WI (US)
- (73) Assignee: **General Electric Company**, Schenectady, NY (US)
- (**) Term: **15 Years**

(21) Appl. No.: **29/612,625**(22) Filed: **Aug. 2, 2017****Related U.S. Application Data**

- (60) Division of application No. 29/537,768, filed on Aug. 28, 2015, now Pat. No. Des. 797,116, which is a continuation of application No. 29/428,371, filed on Jul. 30, 2012, now Pat. No. Des. 741,879.
